UNITED STATES PATENT OFFICE.

NORMAN T. HARRINGTON, OF CLEVELAND, OHIO.

LOAD-HANDLING SYSTEM.

Application filed January 26, 1920. Serial No. 354,123.

To all whom it may concern:

Be it known that I, NORMAN T. HARRINGTON, a citizen of the United States, residing at Cleveland, in the county of Cuyahoga and State of Ohio, have invented a certain new and useful Improvement in Load-Handling Systems, of which the following is a full, clear, and exact description, reference being had to the accompanying drawings.

This invention relates to systems for handling loads, and has for its general object to provide a system of this character which, while capable of operating efficiently over a wide area, is relatively economical of installation. More limitedly, my invention relates to a system or apparatus embodying one or more pivoted towers, with a novel, effective and economical means for counter-balancing the tower or towers in the various positions which they may occupy with reference to their respective supports. Still further objects of the invention will appear hereinafter.

In the drawings forming part hereof, Fig. 1 represents a side elevation of a load-handling system embodying my invention; Fig. 2 an end elevation of one of the towers, the view corresponding substantially to the line 2—2 of Fig. 1; Fig. 3 is a similar view corresponding substantially to the line 3—3 of Fig. 1; Fig. 4 is an end elevation of one of the tower bases and the counterweight, the tower and the counterweight being indicated in varying positions by dotted lines; Fig. 5 is a diagram illustrating the manner of locating the sheaves (or segments thereof) for the cables connecting the towers and their respective counterweights; Figs. 6 and 7 are details in elevation of the upper ends of the towers; Fig. 8 is a diagrammatic elevation of the cables for rocking the towers and for operating the load-handling device; Fig. 9 a plan view of the cableway and rocking cables; Fig. 10 a similar view of the bucket and carriage operating cables; Figs. 11 and 12 elevations of the tower-rocking cables; and Fig. 13 a perspective detail of the counterweight and sheaves.

Describing the parts by reference characters, 1 and 1^a denote a pair of towers, each mounted at its base upon a horizontal pivot 2. A pair of cables 3 are shown as connected to the foundation 4 on each side of each pivot 2 and equidistant therefrom, as by

means of turnbuckles 5. Each cable extends over a segmental guide 6 (concentric with the pivot of its tower) and is connected with a drum 7 on the end of a shaft 8 carried by such tower. As each tower rocks (by application of power to its drum 7) one of the cables of its pair is wrapped upon the drum 7 while a like length of the other cable will be unwrapped, whereby the joint effective length of each pair of cables will be constant. On the opposite end of each shaft 8 from the drum 7 is a gear 9 meshing with a pinion 10 on the end of a shaft 11. Mounted on each shaft 11 is a pair of drums indicated at 12 and 12^a respectively, each pair constituting in effect a single drum. To these drums there are connected cables 13 and 13^a. These cables are secured at their opposite ends to a power drum 14. The cables 13 extend from said drum over sheaves 15 mounted on a carriage 16 supported on a horizontal pivot 16^a to which the tower guy 17 is connected and thence over sheaves 18 to the drums 12. The rocking cables 13^a extend from the power drum over the sheaves 15 and thence over sheaves 19 and 20, at the tops of the two towers and to the drums 12^a. The horizontal pivot 16^a for each guy 17 is in line with the tower pivots 2, whereby the effective lengths of the guys and of the rocking cables are not altered by reason of the rocking of the tower.

Secured to the upper end of each tower is a plate 21 to which the upper end of each guy is connected. Mounted in each plate is a pintle 22, 22^a, the lower end of each pintle being journaled on a shaft 22^b and the axis of the former pintle being parallel with the inclined parts of the cables 23, 23^a, 23^b, and 23^c which open, close and move the bucket 24. The cables 23—23^c extend over sheaves 25, 25^a which are pivoted upon the pintles 22, 22^a. The bucket carriage 26 is mounted upon a cableway 27 one end of which is connected to a yoke 28 also pivoted upon the pintle 22 by a support 28^a while the other end is connected to a tackle 29 and the fixed blocks 30 whereof are pivoted upon the pintle 22^a by means of a support 30^a. The fall 130 of this tackle leads over a sheave 31 at the upper end of the tower 1^a and thence to a drum or winch 32 on the guy carriage 16 of said tower.

The bucket opening, closing and holding lines are operated by a drum 33. The line 110

23 extends from said drum over one of the sheaves 15, thence over one of the sheaves 25 and over the bucket operating sheaves 34 and 35, and its opposite end is secured at 5 36. The line 23^a extends from the same drum over one of the sheaves 15, thence over one of the sheaves 25, and over the bucket operating sheaves 34^a and 35^a and is secured at 10 36^a. The travel line 23^b extends from a drum 37 over one of the sheaves 15, thence over one of the sheaves 25, under the carriage sheaves 37^a, over the sheave 25^a, and is secured to the carriage at 39. The other travel line 23^c extends from 37 over one of 15 the sheaves 15, and one of the sheaves 25 to the bucket carriage, where it is secured, as indicated at 40.

With the parts constructed and arranged as described, by applying power to the drum 20 14, the towers with their interposed cable-way and its load-handling device may be adjusted or rocked in unison to any desired angular extent without altering the lengths (and hence not affecting the supporting efficiency) of the guys 17. Also, because of 25 the manner of mounting the sheaves for the bucket-operating lines as well as the cable-way, a fair lead is given to the bucket-handling lines or cables in all positions of the towers, the sheaves 25 and 25^a being always 30 in line with the cable-way.

In connection with the system thus far described, I provide novel and effective means for counterbalancing the towers and their 35 load in the varying positions which they occupy with respect to their pivots under operating conditions. To each tower a movable counterweight is connected by means of a cable or other flexible connection, this 40 cable extending over a sheave (or a segment thereof) on each side of a vertical line extending from a portion of the tower which is above its center of gravity when the tower is in a vertical position. The axis of each 45 sheave (or segment) is so positioned that the effective lifting effort of the counterweight upon their towers and the load will vary with the effective load to be counterbalanced, thus enabling the towers to be rocked with a minimum expenditure of power and to remain 50 in any position to which they may be moved or rocked and with a minimum amount of braking. In practice, it will be assumed that the counterweights are required to 55 counterbalance the towers, cableway, bucket and half the live load within the latter. The manner in which the location of the axis of each sheave (or sheave segment) is ascertained will be explained in connection with 60 Figs. 4 and 5.

The counterweight for each tower is indicated at 41 and is guided in its vertical movements between uprights 42 supporting at 65 their upper ends horizontal frame members 43, braced by the guys 43^a. Each counter-

weight is shown as connected to its tower at a point above the center of gravity of the tower and its load and preferably near the top thereof by means of a cable 44 which may be pivoted upon a pintle 45. Assume 70 that the effective weight of each tower and its proportion of the weight of the parts associated therewith (including one quarter of the maximum live load in the bucket) is 14500 pounds and that it is desired to use 75 with each tower a counterweight of 28400 pounds. Because of the sag of the cableway and the vertical room occupied by the bucket and its carriage, the extreme operating angle 80 of the towers with respect to the vertical will be about 60°. Let the line *a* denote the central longitudinal axis of the tower, the lower end being pivoted at 2 and *b* the point to which the cable 44 is connected. From the point *b* drop a line *c* representing 85 the load to be counterbalanced (say 14500 pounds). From the lower end of *c* describe an arc which on the scale represented by *c* will correspond to 28400. This arc will intersect *a* at *d*. Draw the line *e* and, at 90 the point *b*, draw *f* parallel with *e*. The line *f* will be tangent to the sheave or segment for the counterweight cable. Repeat this operation for various angular positions of the line *a*. A curve tangent to all the 95 lines *f* on one side of the vertical line *g* will constitute the cable-supporting surface of the sheave or segment. This curve will theoretically be a spiral, but this spiral approximates a segment of a circle 100 with sufficient closeness to enable a circular sheave or segment to be used; and the axis of this sheave or segment may be determined by ascertaining the center *h* of a circle tangent, or substantially tangent to 105 the lines *f* at their intersections as well as tangent to the line *g*. These calculations will enable the opposite sheave or segment to be located. In Fig. 4 the sheave segments are represented at 46 and their centers or 110 pivots at 47. The pivots are supported by the horizontal members 43. Each segment 46 has a track 48 thereon for the cable 44. In order to secure uniformity of movement 115 of the segments by the cables 44 and prevent the counterweight, when elevated, from striking the same as the towers are rocked, the cable 44 is connected to the said segment in the manner shown in Fig. 13. Secured to the cable is a clip or anchor 44^a. To this 120 clip or anchor are secured the upper ends of cables 49, which are adapted to seat in grooves 50 of each segment. The lower end of the cables 49 are secured to projections 51 on the bottoms of the segments. By this 125 connection, the rotation of either sheave segment by the cable will cause the other sheave segment to rock in unison therewith. From the diagram in Fig. 4, it will be understood that the lighter the counterweights, the 130

higher will be the centers or pivots for the sheaves 46 and that, the heavier the counterweights the lower will be the centers or pivots. Also, that whether the counterweights 5 be light or heavy, the angle between f and a will increase as the angle between g and a increases and will decrease as the latter angle decreases.

In operation, as the towers are rocked 10 from a vertical position, each cable 44 will elevate its counterweight and rock its sheave segments about their pivots and will be supported by the segment on that side toward which its tower is moved. The towers and 15 the load thereon will be counterbalanced in all operating positions of the former. Where the segments are located in connection with half the maximum live load in the bucket, the braking effort necessary will be only 20 that which is requisite to compensate for the difference between half the maximum live load and the actual live load. The difference between the effect of a circular support for the cable 44 and the theoretical 25 spiral support in counterbalancing the parts is far less than the percentage of friction necessarily inherent in the moving parts. Hence the towers will remain in any position to which they may be moved with a 30 minimum of expenditure for locking.

When each tower is in a vertical position, the cable 44 passes vertically between the sheaves and supports the entire mass of the counterweight. Among the important 35 advantages secured by my means for counterweighting the towers and their load are the following:

(a) Saving of power for operating the towers.
40 (b) Ability to pivot the towers at their bases, eliminating weight in the towers and the provision of pits for their lower ends.
(c) Securing the full throw of the towers or booms with the use of light towers or 45 booms.

(d) Cheapness of installation.
(e) Wide range and flexibility of operation.

(f) The system is in balance irrespective 50 of the positions of the bucket on the cable-way. The rocking cables 13^a constitute a rotative synchronizing connection between the two towers, so that the effective weight of the towers and of the cable way, bucket, 55 carriage and the predetermined proportion of live load may be accurately balanced irrespective of the distribution of the counterweight. For instance, a single counterweight may be employed (with one tower), 60 or the counterweight carried by one tower may be heavier or lighter than that carried by the other, as long as the total mass of the counterweight is sufficient for the load to be counterbalanced.

65 For convenience of description, the mem-

bers 46 will be referred to hereinafter as "sheaves," it being understood that, by the use of this term, I do not thereby limit myself to the particular shape of such members as is shown herein. Furthermore, it 70 will be evident that the counterweights employed and the location of the sheave pivots may be such as to counterbalance not only the effective weight of the towers, cableway and load-handling device but any desired 75 proportion of the live load. Also, if desired, a single counterweight may be employed with one only of such towers, in which case, the mass of the counterweight will be correspondingly increased; also that the term 80 "tower" is employed in its broad sense herein and includes what is known in this art as a boom or derrick.

Having thus described my invention, what I claim is:—

85

1. The combination with a tower supported for angular movement in a substantially vertical plane and means including a counterweight movable relatively to the tower for counterbalancing the tower in 90 substantially all angular positions on both sides of its vertical position.

2. The combination with a tower supported for angular movement in a substantially vertical plane and means including 95 a counterweight movable relatively to the tower and a flexible connection between the tower and the counterweight for counterbalancing the tower in substantially all angular positions on both sides of its vertical 100 position.

3. The combination with an angularly movable tower, of a counterweight, a flexible connection between the counterweight and the tower and means operative to determine the direction of pull of the flexible connection for varying angular positions of the tower on both sides of its vertical position so as to substantially counterbalance the latter in all of such positions. 110

4. The combination with an angularly movable tower, of a counterweight, a flexible connection between the counterweight and the tower and means operative to determine the direction of pull of the flexible 115 connection for varying angular positions of the tower on both sides of its vertical position so as to substantially counterbalance the latter in all of such positions, said means including elements having each a curved 120 surface forming a bearing surface for the flexible connection.

5. The combination with an angularly movable tower, of a counterweight, a flexible connection between the counterweight 125 and the tower and pivoted elements having each a curved surface affording a bearing for the said flexible connection, said elements being positioned on opposite sides of the flexible connection and on opposite sides 130

of the central vertical plane through the tower.

6. The combination with an angularly movable tower, of a counterweight, a flexible connection between the counterweight and the tower and pivotally supported segments affording a bearing for the flexible connection, said segments being positioned on opposite sides of the central vertical plane through the towers.

7. The combination with a pivotally supported tower, of a counterweight, a flexible connection between the counterweight and the top portion of the tower, an element pivotally mounted above the pivot point of the tower and affording a bearing for the flexible connection, the bearing surface of the element defining a curve substantially tangent to the central vertical plane through the tower.

8. The combination with a pivotally supported tower, of a counterweight, a flexible connection between the counterweight and the top portion of the tower, a segment pivotally mounted above the pivot point of the tower and affording a bearing for the flexible connection, the segmental bearing surface being substantially tangent to the central vertical plane through the tower.

9. The combination with an angularly movable tower, of a counterweight, a flexible connection between the counterweight and the tower and two elements mounted upon opposite sides of the central vertical plane through the tower and having curved surfaces affording bearings for the said connection when the tower is disposed on one or the other side of said plane respectively.

10. The combination with an angularly movable tower, of a counterweight, a flexible connection between the counterweight and the tower, two segments pivotally supported upon opposite sides of the central vertical plane through the tower above the pivot point thereof, said segments being substantially tangent to said plane and affording bearing surfaces for the flexible connection.

11. The combination with an angularly movable tower, a counterweight movable in the general plane defined by the vertical position of the tower, a flexible connection between the upper portion of the tower and the counterweight, two segments pivotally supported above the counterweight and substantially tangent to the said plane at opposite sides thereof and means operative during movement of the said connection for moving the segments about their pivots in the direction of movement of the said connection.

12. The combination with a tower supported for angular movement in a substantially vertical plane, a counterweight movable in the general plane defined by the verti-

cal position of the tower, a flexible connection between the upper portion of the tower and the counterweight, two segments pivotally supported above the counterweight and substantially tangent to the said plane at opposite sides thereof and flexible means extending from the lower sides of the segments to a point of the flexible connection between the segments and the tower for imparting movement to the segments from the said flexible connection.

13. The combination with two angularly movable towers, a cable way extending between and supported by the towers and means for moving the towers in unison, said means comprising a shaft revolvably mounted on each tower transversely of the direction of motion thereof, means for simultaneously operating the shafts, circular tracks corresponding to the paths described by the shafts during the movement of the towers and means between the shafts and the said tracks for causing the towers to move when the shafts are revolved.

14. Apparatus according to claim 13 including a drum on each shaft and a cable wound about the drum and extending in opposite directions along the surface of the track to fixed anchoring points.

15. The combination with two angularly movable towers, a cable way extending between and supported by the towers and means for moving the towers in unison, said means comprising a drum on each tower, a pair of cables running from a point in the central vertical plane through the towers and at one side thereof over sheaves in the upper part of the first tower to the drum of that tower and wound in opposite directions thereon, a pair of cables running from the same point over sheaves on the first tower and sheaves near the top of the second tower to the second drum and wound in opposite directions thereon, means for simultaneously operating the cables and means for translating the motion of the drums for moving the towers.

16. The combination with two angularly movable towers, a cable way extending between and supported by the towers, a drum on each tower, cables for revolving the said drums, means for translating the movement of the drums to move the towers and a power drum for operating the cables, the cables passing from the power drum over sheaves positioned in the central vertical plane of the towers and in a line passing through the pivot points of the towers, over sheaves near the top of the first tower, and one cable passing to the drum on said first tower while the second cable passes over a sheave near the top of the second tower to the second drum.

17. Apparatus according to claim 16 including hold down cables anchored in a line

passing through the pivot points of the towers and the cables coming from the power drum passing substantially through the anchoring point of one of the towers.

5 18. The combination with two angularly movable towers, a cable way between and supported by the towers, hold down cables anchored in points in alignment with the pivot points of the towers, a drum on each

10 tower means co-operating with the drums for moving the towers, a power drum and cables passing from the power drum sub-

stantially through the anchoring point of one hold down cable and to the top of the

15 tower held thereby, one cable passing to the drum of the first tower and the other cable passing to the top of the second tower and to the second drum.

19. The combination, with a pair of

20 towers, a cableway extending between and supported by said towers and a load-hand- dling device on said cableway, of means connect-

25 ing said towers for rocking the same in unison, a vertically movable counterweight for each tower, a flexible connection be-

30 tween each tower and its counterweight, and a sheave pivoted on each side of each tower pivot and above the same and adapt-

35 ed to be engaged by said connection as its tower is rocked to one side or the other of a vertical position.

20. The combination, with a pair of

towers, a cableway extending between and supported thereby and a load-handing de-

35 vice on said cableway, of means connecting said towers for rocking the same in unison, a vertically movable counterweight for one at least of said towers, a flexible connection between such tower or towers and such

40 counterweight or counterweights, and a pair of supports for each connection and adapt-

ed to be engaged by such connection when its tower is moved to one side or the other from a vertical position, the said supports

45 being so arranged that the weight of the towers, cableway, load-handling device and a definite proportion of the live load will be counterbalanced in all angular positions of said towers.

50 21. The combination, with a pair of towers, a cableway extending between and supported by said towers, and a load-handling device movable along said cable-

55 way, of a counterweight movable with respect to at least one of said towers, means connect-

60 ing said towers for rocking the same in unison, and means connecting each such counterweight and its tower whereby the tower-lifting effort of the counterweight

65 will vary with the angular movements of the towers from the vertical about their centers of rotation.

22. The combination, with a pair of tow-

ers, a cableway extending between and sup-

65 ported thereby and a load-handling device

on said cableway, of a movable counter- weight for each tower, means connecting said towers for rocking the same in unison, and means connecting each counterweight and its tower whereby the said towers, cable- 70 way, load-handling device and a definite proportion of the load carried by said device will be counterbalanced in varying angular positions of said towers and in varying positions of the load-handling device on the cableway.

23. The combination, with a pair of tow- 75 ers, a cableway extending between and sup- ported by said towers, and a load-handling device movable along said cableway, of a 80 counterweight movable with respect to at least one of said towers, means connecting said towers for rocking the same in unison, a connection between each such counter- weight and the upper portion of its tower 85 and guiding and supporting means co-oper- ating with each such connection for varying the angle at which the counterweight oper- ates upon the tower in accordance with the movement of the latter from a vertical posi- 90 tion.

24. The combination, with a pair of tow- 95 ers, a cableway extending between and sup- ported by said towers, and a load handling device on said cableway, of means for rock- ing said towers, a vertically movable counterweight for each tower, a flexible connec- 100 tion between each tower and its counter- weight and a sheave pivoted on each side of each tower pivot and above the same and adapt- ed to be engaged by said connection as its tower is rocked to one side or the other of a vertical position.

25. The combination, with a pair of tow- 105 ers each having a pivot at the lower end thereof, a cableway extending between and supported by said towers and a load han- dling device on said cableway, of a vertically movable counterweight for each tower, a 110 flexible connection between each counter- weight and the upper portion of each tower, a pair of sheaves for each tower, the pivots for such sheaves being located on opposite sides of the connection for their tower and each adapted to be engaged by such connec- 115 tion as their tower is rocked to one side or the other of a vertical position, and means connect- ing the sheaves of each pair whereby the rocking of one sheave by the said connec- 120 tion will cause the rocking of the other sheave.

26. The combination, with a pair of tow- 125 ers, a cableway extending between and sup- ported thereby and a load-handling device on said cableway, of means for rocking said towers in unison, a vertically movable counterweight for each tower, a flexible connec- 130 tion between each tower and its counter- weight, and a pair of supports for each connec- tion, and adapted to be engaged by such

connection when its tower is moved to one side or the other from a vertical position, the said supports being so arranged that the weight of the towers, cableway, load-handling device and a definite proportion of the live load will be counterbalanced in all angular positions of said towers.

27. The combination, with a pair of towers, a cable way extending between and supported thereby and a load-handling device on said cableway, of a movable counterweight for each tower, and means connecting each counterweight and its tower whereby the said towers, cableway, load-handling device and definite proportion of the load carried by said device will be counterbalanced in varying angular positions of said towers.

28. The combination, with a tower and a pivot therefor, of a drum carried by said tower, a segmental guide, a pair of cables each connected at one end to said drum and extending in opposite directions therefrom over the adjacent surface of said guide and having their opposite ends anchored, and means for rotating said drum in opposite directions.

29. The combination with a tower and a pivot therefor of a shaft supported by said tower, a drum on said shaft, a segmental guide adjacent to said drum, a pair of cables each connected at one end to said drum and extending in opposite directions therefrom and over the adjacent surface of said guide and having their opposite ends anchored, a gear on said shaft, a second shaft supported by said tower, a drum on said second shaft and a gear on such shaft meshing with the first mentioned gear, and means for driving the second drum.

40 30. The combination, with a pair of towers, a cable way extending between and supported thereby and a load-handling device on said cableway, of a pivot for each tower, a pivot at one side of each tower and in line with the first mentioned pivots, a carriage on each of the second mentioned pivots, a guy connecting each carriage with the upper portion of a tower, and means for rocking the towers about their pivots.

50 31. The combination, with a pair of towers, a cable way extending between said towers and a load-handling device on said cableway, of a pivot for each tower, a pivot on one side of each tower and in line with the first mentioned pivots, a carriage on each of the second mentioned pivots, a guy connecting each carriage with the upper portion of a tower, sheaves on one of said carriages, cables extending over said sheaves to the upper portion of one of said towers, a pintle extending substantially parallel with the portions of said cables extending from said sheaves, a sheave support journaled on said pintle, sheaves on said support

for said cables, and connections between said cables and said device.

32. The combination, with a pair of towers, of an upwardly and inwardly inclined pintle adjacent the upper end of each tower, a cableway support journaled on each pintle, a sheave support journaled on each pintle, a load handling device movable along said cableway, cables extending about said sheaves and connected with said device, and means for rocking said towers.

33. A load-handling system comprising two angularly movable towers, a cableway between and supported by the towers, means for moving the towers in unison, and means for counterbalancing the system in the different angular positions on both sides of a vertical plane, said means including a weight movably connected to one of the towers.

34. A load-handling system comprising two angularly movable towers, a cableway between and supported by the towers, means for moving the towers in unison, and means for counterbalancing the system in the different angular positions on both sides of a vertical plane, said means including a weight movably connected to each of the towers.

35. A load-handling system comprising two angularly movable towers, a cableway between and supported by the towers, means for moving the towers in unison, and means for counterbalancing the system in the different angular positions on both sides of a vertical plane, said means including a weight mounted for vertical movement adjacent one of the towers, flexible means for connecting the weight to the upper part of the tower and a guiding support for the connecting means intermediate the weight and the tower.

105 36. Apparatus according to claim 35 in which the guiding support includes two curved members disposed on opposite sides of the plane passing through the center of the towers when in vertical position.

110 37. Apparatus according to claim 36 in which the curvatures of the members are substantially tangent to the said plane.

38. Apparatus according to claim 36 in which the members are pivotally mounted.

115 39. The combination with a tower and means for rocking the same, of a load-handling device supported by said tower, a movable counterweight, and means connecting said tower and counterweight whereby the tower and its load-handling device will be counterbalanced in varying angular positions of the tower and on opposite sides of a vertical position.

120 40. The combination with a tower, a load-handling device supported thereby and means for rocking said tower, of a movable counterweight, and means connecting said counterweight and tower, whereby the tower-lifting effort of the counterweight

will vary with the angular movement of the tower from the vertical about its center of rotation and on both sides of such center.

41. The combination with a tower and a load-handling device supported thereby, of means for rocking said tower, a movable counterweight, a flexible connection between said tower and counterweight, and means located on each side of said connection and adapted to be engaged thereby whereby the

counterweight will be raised by the movement of the tower from a vertical position and the angle between said connection and said tower will vary in accordance with the angular movement of the tower from such 15 vertical position.

In testimony whereof, I hereunto affix my signature.

NORMAN T. HARRINGTON.
